Primary Examiner — Brett Miller(74) *Attorney, Agent, or Firm* — Browdy and Neimark, PLLC(57) **CLAIM**

The ornamental design for a mirror booth, as shown and described.

DESCRIPTION

FIG. 1 is a top-front perspective view of a mirror booth showing my new design;

FIG. 2 is a bottom-front perspective view thereof;

FIG. 3 is a top-rear perspective view thereof;

FIG. 4 is a bottom-rear perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

The broken lines immediately adjacent the shaded areas represent the bounds of the claimed design while all other broken lines are direct to environment and are for illustrative purposes only; the broken lines form no part of the claimed design.

1 Claim, 10 Drawing Sheets(56)
